US007533885B2

(12) **United States Patent**
Nicely et al.

(10) **Patent No.:** US 7,533,885 B2
(45) **Date of Patent:** May 19, 2009

(54) **GAMING DEVICE HAVING A ROTOR-BASED GAME WITH A BONUS OPPORTUNITY**

(75) Inventors: **Mark Nicely**, Daly City, CA (US); **Paul Miltenberger**, Las Vegas, NV (US)

(73) Assignee: **IGT**, Reno, NV (US)

(*) Notice: Subject to any disclaimer, the term of this patent is extended or adjusted under 35 U.S.C. 154(b) by 0 days.

(21) Appl. No.: **11/064,314**

(22) Filed: **Feb. 23, 2005**

(65) **Prior Publication Data**

US 2006/0237905 A1 Oct. 26, 2006

(57) **ABSTRACT**

A standard underlying multi-outcome/multi-bet game is played, whereby a bonus mechanism can reward the player relative to their underlying game bets. Such a bonus may be triggered by a underlying game outcome (which may or may not be an outcome which a bet can be placed) or by an event independent of the underlying game. A bonus reward can be the playing of one or more plays of the underlying game, optionally with different play rules and/or pay schedules.

GAMING DEVICE HAVING A ROTOR-BASED GAME WITH A BONUS OPPORTUNITY**PRIORITY CLAIM**

The present application claims priority to, and the benefit of, U.S. Provisional Application Ser. No. 60/547,643 entitled "Bonus Structures for Multi-Outcome/Multi-Bet Gambling" filed Feb. 23, 2004 by Applicant herein.

CROSS REFERENCE TO RELATED APPLICATIONS

The present application relates to the following commonly-owned pending patent applications: U.S. patent application Ser. No. 11/558,777 filed on Nov. 10, 2006, U.S. patent application Ser. No. 11/119,997 filed on May 2, 2005, U.S. patent application Ser. No. 11/609,173, filed on Dec. 11, 2006, and U.S. patent application Ser. No. 11/609,149, filed on Dec. 11, 2006.

FIELD OF THE INVENTION

The present invention relates to the field of betting games having multiple events and permitting of multiple bets. Specifically, the present invention is an improved method for conducting such a betting game, wherein a bonus reward occurs which pays against underlying game bets, triggered by specified outcome events or by an event independent of the underlying game. In one embodiment, the bonus reward is resolved within the play of the underlying game of chance.

BACKGROUND OF THE INVENTION

Slot games and other games of chance have experienced significant increases in their popularity and they profitability. Much of this new interest may be credited to a wealth of improvements, including in particular the addition of bonus events and bonus rewards. Such additions exhibit additional ways for the player to win, and so increase the interest in, and excitement of, the game. Despite generally seeing no improvement in their expectation of win, all but the most experienced player are likely to find the extra excitement sufficient justification for additional play.

Such bonus potential may add new elements of interest to multi-outcome/multi-bet games like roulette, money wheel, dice sum, and simulated racing. A multi-outcome/multi-bet game is herein defined as a game which may produce multiple game outcomes and which offers the player the ability to place bets on these several outcomes. Traditionally, the player must bet on a particular outcome in order to receive any reward for that outcome. Herein we add an improvement which can allow all bets to justify a bonus reward.

The traditional game of roulette consists of a horizontally aligned wheel divided into equal sized sectors, typically referred to as canoes, each said canoe being assigned a non-unique color and a unique number. Typically, the colors available are Red, Black, and Green, and numbers range from 1 to 36, augmented by 0 and 00, although the 00 designation is not universally used. Typically, roulette when played in Europe only utilizes a 0 designation, not a 00.

A round of play commences when, after the players have placed their bets, the house dealer spins the roulette wheel, and subsequently releases a ball into the spinning wheel. The ball eventually comes to rest in one of the canoes on the wheel. The designators assigned to the canoe in which the ball came to rest determine the several outcomes of the game.

2

Such designators consist of the number associated with the canoe, the color, and the odd-of-even attribute. Note: 0 and 00 are not considered either odd or even numbers.

5 Players may bet on any or all of the result characteristics, the specific number, the color, or the odd/even characteristic. Number bets may be placed on individual numbers, or pre-defined groups of numbers. Game bets allow betting on 1, 2, 3, 4, 5, 6, 12, or 18 numbers. The larger the group on which the 10 bet is placed, the lower the payout associated. Thus, a bet on the number 7 may be paid at 34 to 1, but a bet on the group 1-12 may be paid at 2 to 1. Typically, players may place an unlimited number of such bets, each bet evaluated independently of other bets, and, if appropriate, paid.

15 Money wheel (sometimes referred to as the "Big 6") is another popular casino multi-outcome/multi-bet game. The game consists of a vertically aligned wheel sectioned off into equal sized sectors, each said sector associated with a certain 20 reward amount. Pegs at the edge of the wheel engage a flipper or marker that indicates which sector is the selected one. In an electronic or video game format, lights or highlighting can be used to designate the selected sector. Typically, the probability associated with a lower reward, i.e. the number of sectors associated with such a lower reward, or the programmed likelihood of its occurrence, is higher than the probability associated with a higher reward.

25 A play is initiated once players have placed one or more 30 bets, by having a sector randomly selected. For a mechanical wheel, this is done by spinning the wheel and determining which sector the flipper denotes. For an electronic or video game version using lights or highlighting, the final sector is often selected by chase-light sequence whereby sectors are lit sequentially until the sequence stops and the final sector lit is designated as the sector selected.

35 A choice of potential bets are offered for the different 40 outcomes whereby the player will be rewarded if he correctly predicts the reward amount associated with the wheel sector selected. For example, the player can bet that a sector featuring a \$1 reward will be selected, or he can bet that the sector featuring a \$5 reward, and so forth. Typically, the player is allowed make a number of simultaneous bets.

45 Another example of a multi-outcome/multi-bet game is a simulated racing game. Such a game uses a multiplicity of 50 avatars engaging in a race, often depicted as horses or other animals or ships, cars, or other vehicles. The player may then bet on the relative finishing position of one or more of the avatars. For example, one electro-mechanical implementation of this game allows a player to bet on which one of 6 plastic horses will cross the finish line first in a simulated race. One video game implementation permits players to bet on 55 which of 8 turtle characters will cross the finish line first in a simulated race. Often, such games the likelihood that a given avatar will finish first will vary by avator. The reward associated with each avatar varies accordingly.

60 Yet another multi-outcome/multi-bet game is a dice sum game such as Craps or Sic Bo. Certain sums are more like to occur than other sums. For example, there is only way to roll a sum of 12 with two dice (6+6), but there are six ways to roll a sum of 7 (6+1, 5+2, 4+3, 3+4, 2+5, 1+6). Such a game can be offered such that multiple simultaneous bets are possible.

65 Such multi-outcome/multi-bet games typically do not include a bonus reward component. As other categories of

games have benefited from the popularity of such innovations, so too may these, and other, multi-outcome/multi-bet games.

SUMMARY OF THE INVENTION

This invention involves adding a bonus structure to multi-outcome/multi-bet casino games which pays against the bets made on the underlying game. Such bonus events can be triggered by a standard outcome of the underlying game upon which the player can bet, or an additional outcome of the underlying game upon which the player cannot bet, or by an event independent of the underlying game. This invention further involves adding a bonus structure to multi-outcome/multi-bet casino games by designating certain rounds as bonus rounds with special rules and/or pay opportunities for wagers placed in the underlying game of chance.

In one optional embodiment, the bonus mechanism is initiated on a random basis by a randomizing technique such as the random selection of a special bonus ball or other such method. This can be accomplished by utilizing balls of different colors, at least one of which is designated as a bonus triggering event, or by an external event such as spinning a wheel, drawing a card from a shuffled deck, etc. Alternatively, the bonus mechanism may be implicated as a result of a game outcome, with specified game outcomes being designated as bonus triggering events. In another alternative embodiment, the bonus mechanism might be implicated whenever a standard game wager, or a selected group of standard game wagers, exceeds a predefined minimum.

In an optional embodiment, a bonus round for such an improved game could involve multiple spins not requiring the placing of an additional wager, or an increase in the reward amounts for winning outcomes during that round. A bonus round could also invoke an independent proposition which could lead to a specific reward or to an increase in a normal game reward. For example, a spinner could randomly specify a multiplier effect for any reward won in the standard game or in the bonus round.

In another optional embodiment, when applied to the game of roulette, this invention could involve the addition of at least one bonus sector or canoe. If the ball lands in such a bonus canoe, this could constitute a bonus triggering event. In one optional embodiment, such an event might increase a bonus accumulator. When such bonus accumulator reaches a predefined threshold amount, a bonus round could be initiated. In an alternate embodiment, a bonus event could be directly initiated upon having the ball land in a bonus canoe.

In one optional embodiment, the bonus event could lead to a direct pay based upon total bets. In another optional embodiment, the bonus event could be a special bonus spin. In such an embodiment, the original wagers could stand and any payout for winning outcomes in the bonus spin could be larger than standard, e.g. double the standard amount. Alternatively, the original wagers could stand and the player get a multiplicity of bonus spins, e.g. two free bonus spins. In an alternate embodiment, rather than a reward of 'n' bonus spins, the reward might be a single round utilizing 'n' balls. In an alternate embodiment, this could include a provision that no two bonus balls could share the same canoe or alternatively that multiple bonus balls could share the same canoe.

In an optional embodiment, the outcome of a bonus round might be the bonus triggering outcome. In an optional embodiment, this could negate the prior bonus reward. Alternatively, this could lead to an additional bonus reward. In one such embodiment, this could lead to a bonus round utilizing altered pay characteristics. For example, such a compound

bonus triggering event could lead to the selection of a random reward multiplier, said reward multiplier being applied to any bonus reward otherwise generated. In an alternate embodiment, the bonus outcomes could be disabled during the bonus round.

In an optional embodiment, a separate bonus wager may be offered. Such a wager may either be required to receive a bonus reward, or might increase such resulting bonus reward.

In an optional embodiment of this invention being applied to roulette, the probability of a bonus canoe being selected might have different odds of being selected than do standard canoes. In a mechanical device, this can be accomplished by having the bonus canoe be of a different size as the regular canoes, altering the probability of the roulette ball coming to rest in a bonus canoe. For example, a roulette wheel with 38 regular canoes and 1 bonus canoe could have the bonus canoe twice the size of a standard canoe, thereby making it twice as likely of selection. For an electronic version of this invention, such differentiation of probability may be accomplished by such programming as is currently known in the art.

The above alternate implementations may be applied in similar ways to a money wheel type game. A bonus sector might be added to the wheel, as could secondary or bonus flippers or markers.

The present invention might also be applied to games of simulated racing. In such games, a bonus can be initiated by the final position of a specified avatar. For example, a bonus could be activated if the most favored avatar (the avatar with the highest probability of finishing first) finishes the simulated race last. Alternatively, a special bonus avatar might be utilized, on which no bets could be placed and whose sole purpose would be the triggering of a bonus outcome. Such alternatives might implicate a single avatar, or a multiplicity of avatars, and might involve finishing first, last, or at any other predesignated positions.

This invention may also be applied to a dice sum game, wherein certain outcomes can be specified as bonus triggering outcomes. Bonus rewards may be of types previously defined. Alternatively, the dice sum game may utilize alternate bonus reward mechanisms.

In one such mechanism, a bonus event can be initiated which determines bonus rewards based upon the cumulative total of the bonus triggering outcome and one or more subsequent game outcomes. Thus, if for example dice throws totaling 3 or 11 are specified as bonusing initiating outcomes, a player rolling an 11 in the underlying game would initiate a bonus reward. If, on his next roll such player were to roll a 12, this would be accumulated with the prior roll of 11 for a total of 23. As summation of multiple rolls allows totals exceeding that of an ordinary play of the game, special bonus rewards might be accorded on such higher totals only. Alternately the accumulation might be performed in a wrap around methodology, using "modular arithmetic" or its equivalent.

In one such implementation, a bonus mechanism game can be created where the cumulative totals are indicated along the edges of a square or rectangle. For example, the values 1 through 5 might be indicated along one edge of a square, 5 through 9 along the next edge, 9 through 13 along the next edge and 13,14,15,16,1 along the last edge. Moving about this square on each bonus triggering or bonus roll causes such total to "wrap" whenever it exceeds 16. For example, using the previous example of a bonus roll of 12 following a bonus triggering roll of 11 yields a total of 23, but in a board configuration, this results in a value of 7. (Utilizing modular arithmetic notation, $12+11=7(16)$.) Therefore the cumulative value of 7 would be used for bonus reward determination.

In another alternative, such bonus reward mechanism might continue as long as designated bonus continuing outcomes are generated. For example, if a bonus roll is a double, two die of matching value, an additional bonus roll might be involved. Should the bonus reward resolution indicate a bonus reward following each bonus triggering roll and each bonus roll, this would cause a continue, and growing, bonus reward. Additionally, the bonus rewards so determined could be altered each time the bonus square is completed, i.e. each time the cumulative total exceeds 16 and is thereby modulated.

BRIEF DESCRIPTION OF THE DRAWINGS

FIG. 1 is a top view of a roulette inside bet area;

FIG. 2 is a top view of a roulette inside bet area with separate bonus bet area according to an embodiment of the present invention;

FIG. 3 is a top view of a roulette inside bet area with bonus bet area integrated at top according to an embodiment of the present invention;

FIG. 4 is a top view of a roulette inside bet area with bonus bet area integrated according to an embodiment of the present invention;

FIG. 6 is a top view of a dice sum game with bonus outcomes according to an embodiment of the present invention;

FIG. 7 is a top view of a dice sum game with rethrow and wrap around features according to an embodiment of the present invention;

FIG. 8 is a top view of a dice sum game with rethrow and wrap around and bonus square features according to an embodiment of the present invention;

FIG. 9 is a dice sum game with rethrow and wrap around and bonus squares and combination bet features according to an embodiment of the present invention;

FIG. 10 is a flow diagram of a method with a bonus round selected before outcome according to an embodiment of the present invention;

FIG. 11 is a flow diagram of example game with bonus outcomes according to an embodiment of the present invention;

FIG. 12 is a flow diagram of bonus round with one replay at higher reward schedule according to an embodiment of the present invention;

FIG. 13 is a flow diagram of bonus round with multiple sequential replays according to an embodiment of the present invention;

FIG. 14 is a flow diagram of bonus round with multiple parallel replays according to an embodiment of the present invention;

FIGS. 15A and 15B are a flow diagram of a possible dice sum game with a bonus according to an embodiment of the present invention.

FIG. 16 is a schematic diagram of one embodiment of a multi-outcome/multi-wager game with a bonus round.

DESCRIPTION

Reference is now made to the figures wherein like parts are referred to by like numerals throughout. Throughout the optional embodiments illustrated herein, it is contemplated that the term "bonus rewards" are determined based upon wagers placed the underlying game. Furthermore, bonus rounds may be of fixed duration, or may be of a length as determined by outcomes generated during the execution of

the bonus rounds, said results extending or curtailing the bonus generation as indicated according to the prespecified rules of play.

For purposes of illustration, bonus triggering and bonus extending outcomes are predefined per prespecified rules of play. In alternate embodiments, such bonus triggering and bonus extending outcomes may be randomly, and dynamically, defined.

FIG. 1 illustrates the traditional roulette inside wagering area 100 including sample wagers 121, 122, 123. All game outcomes comprising the standard roulette wheel are represented within this inside wagering area 100. Wagers 121, 122, 123 may be placed which will be rewarded on the occurrence of one or more of these standard game results. The \$1 wager 121 will be rewarded should either of two game outcomes, "6" 110 or "9" 111, occur. The \$2 wager 122 will be rewarded only should the outcome "12" 112 occur. The \$3 wager 123 will be rewarded if any one of three outcomes, "34" 113, "35" 114 or "36" 115, occur.

FIG. 2 depicts an alternate embodiment of a roulette inside wagering area 200 which has added a bonus wagering location 230. A sample \$4 bonus wager 224 is illustrated, betting solely on such a bonus outcome. Non-bonus wagers made in this game 221, 222, 223, are nonetheless eligible for bonus rewards as determined in the bonus event whether or not a bonus wager 224 has been placed. In fact, in an alternate embodiment of this game, such a bonus wager 230 need not be available, and the inside wagering area 200 for such bonus-enhanced games may be indistinguishable from the inside wagering area 100 for the standard game as shown in FIG. 1.

FIG. 3 depicts an alternate embodiment of a roulette inside wagering area 300 wherein the bonus wagering opportunity 330 has been integrated into the standard wagering design. In addition to such bonus wagers as previously described 328, this embodiment facilitates wagers on combinations of game and bonus outcomes 325, 326 and 327. The \$4 sample wager 325 is rewarded should either a bonus outcome 330 occur or should a "0" 316 occur. This effectively places a \$2 wager on a bonus outcome 330 and a \$2 wager on the "0" outcome 316. The \$6 sample wager 326 is rewarded should either a bonus outcome 330 occur or should a "00" 317 occur. This effectively places a \$3 wager on a bonus outcome 330 and a \$3 wager on the "00" outcome 317. The \$9 sample wager 326 is rewarded should bonus outcome 330 occur, should a "0" 316 occur, or should a "00" 317 occur. This effectively places a \$3 wager on a bonus outcome 330, a \$3 wager on the "0" outcome 316, and a \$3 wager on the "00" outcome 317. For purpose of illustrations, amounts wagered were varied for descriptive clarity, but in an actual game, all of the wagers can typically be of the same amount.

In general, wagers on combinations of numbers offer two advantages: 1) they allow a player to have some control balancing risk and reward, wherein a wager on a larger set of potential winning outcomes increases the probability of obtaining such a winning outcome, but reduces the ratio of the reward of such a winning outcome to the amount wagered, and 2) combination wagers simplify the practice of placing multiple wagers, in particular where the size of the combination wager is large enough to approximate the sum of the equivalent individual wagers. For example, the \$3 combination wager 323 for outcomes "34" 313, "35" 314 and "36" 315 could be made as three separate \$1 wagers, one on each of the indicated outcomes, should \$1 wagers be permitted, but placing a single combination wager 323 requires less effort, on the

part of the player as well as on the house. Furthermore, if the minimum wager is \$1, the player could make a \$1 wager on the combination “34” 313, “35” 314 and “36” 315 even where a wager of \$1/3 for each such outcome would not be permitted.

FIG. 4 depicts a roulette inside wagering area 400 with an alternate embodiment of the integration of the bonus wagering location 430. In this embodiment, the bonus wagering location 430 is appended to one of the long sides of the standard inside wagering area 400. In addition to direct bonus wagers 425, this configuration also allows extensive combination wagers which combinations of game and bonus outcomes 424, 426 and 427. The \$6 sample wager 426 is is rewarded should a bonus outcome 430 occur or should a “24” 419 occur. This effectively places a \$3 wager on a bonus outcome 430 and a \$3 wager on the “24” outcome 419. The \$4 sample wager 424 is rewarded should a bonus outcome 430 occur, should a “31” 416 occur, should a “32” 417 occur or should a “33” 418 occur. This effectively places a \$1 wager on a bonus outcome 430, a \$1 wager on an outcome of a “31” 416, a \$1 wager on an outcome of a “32” 417, and a \$1 wager on an outcome of a “33” 418. The \$7 sample wager 427 is rewarded should a bonus outcome 430 occur, should a “31” 416 occur, should a “32” 417 occur, should a “33” 418 occur, should a “34” 413 occur, should a “35” 414 occur, or should a “36” 415 occur. This effectively places a \$1 wager on a bonus outcome 430 and a \$1 wager on each of the outcomes “31”, “32”, “33”, “34”, “35” and “36” 413-418. This embodiment still allows game wagers across three numbers such as the sample wager \$3 443 on the combination of outcomes “34” 413, “35” 414 and “36” 415 without requiring this combination to also include the bonus outcome.

While not illustrated in the embodiments illustrated, alternate embodiments include configurations wherein combination wagers are available which incorporate bonus wagers with other game wagers, such as the game outside wagers (RED, BLACK, HIGH, LOW, EVEN, ODD, 1st DOZEN, 2nd DOZEN, 3rd DOZEN, 1st COLUMN, 2nd COLUMN, 3rd COLUMN).

While the payouts could take any form and are not restricted to any specific form or quantity, Table 1 illustrates an example pay table for a roulette game according to the embodiment of FIGS. 2-4.

TABLE 1

Inside Bets	
Straight Bets	35 to 1
Split Bets	17 to 1
Trio Bet	11 to 1
Corner Bet	8 to 1
Five-number Bet	6 to 1
Six-number Bet	5 to 1
Outside Bets	
Dozens	2 to 1
Column	2 to 1
Even-odd	1 to 1
Red-black	1 to 1
High-low	1 to 1

If Standard Ball Lands on Yellow, All Bets Stand and Double Ball Bonus Round Commences.

Yellow Bonus Bets

	Standard Ball on Yellow	1 Bonus Ball on Yellow	Both Bonus Balls on Yellow
Straight Yellow Bet	12x Bonus Bet	120 to 1	1200 to 1
Split Yellow Bet	6x Bonus Bet	60 to 1	600 to 1
Trio Yellow Bet	4x Bonus Bet	40 to 1	400 to 1

In one embodiment, an improved method further comprises excluding one or more canoes from receiving the one or more balls during the subsequent plays of the underlying game, thereby increasing the likelihood of other canoes receiving the balls. Each of the other canoes is associated with a bonus reward. In one embodiment, a canoe is excluded by using a second roulette wheel distinct from the roulette wheel with the canoes corresponding to the excluded canoes not present in the second roulette wheel. In one embodiment, a canoe is excluded by using a second roulette wheel distinct from the roulette wheel with the canoes corresponding to the excluded canoes filled such that a ball cannot land in the excluded canoe.

FIG. 5 depicts an optional embodiment for a traditional dice sum game 500. In this embodiment, the player may place a wager on any of the wagering areas 502 through 512 and as is indicated in the instructions 530, and is rewarded if an outcome on which he has wagered results occurs on the next throw of two standard dice. Referring to the wagering area for the outcome “5” 505 as an example, the wagering area lists the outcome being wagered upon 520 and the reward ratio to be paid on such a wager should that outcome 520 occur.

Referring now to FIG. 16, this invention involves adding a bonus structure to multi-outcome/multi-bet casino games or gaming devices 10 which pay against the bets 12 made on the underlying game at wagering stations 14. Such bonus events can be triggered by a standard outcome 16 of the underlying game upon which the player can bet, or an additional outcome 18 of the underlying game upon which the player cannot bet, or by an event independent of the underlying game. This invention further involves adding a bonus structure to multi-out/multi-bet casino games by designating certain rounds as bonus rounds with special rules and/or pay opportunities for wagers placed in the underlying game of chance.

In one embodiment, when applied to the game of roulette 20, this invention could involve a rotor 22 with regular or standard canoes 16 and at least one bonus sector or canoe 18. If the ball lands in such a bonus canoe 18, this could constitute a bonus triggering event or bonus outcome 24. In one optional embodiment, such an event might increase a bonus accumulator. When such bonus accumulator reaches a predefined threshold amount, a bonus round could be initiated. In an alternate embodiment, a bonus event could be directly initiated upon having the ball land in a bonus canoe 18.

In an optional embodiment of this invention being applied to roulette 20, the probability of a bonus canoe 18 being selected might have different odds of being selected than standard canoes 16. In a mechanical device, this can be accomplished by having the bonus canoe 18 be of a different size as the regular canoes 16, altering the probability of the roulette ball coming to rest in a bonus canoe 18. For example, a roulette wheel with 38 regular canoes and 1 bonus canoe could have the bonus canoe 18 twice the size of a standard

canoe, thereby making it twice as likely of selection. For an electronic version of this embodiment, such differentiation of probability may be accomplished by such programming 26 as is currently known in the art.

FIG. 6 illustrates an alternate embodiment 600 of the present invention to that depicted in FIG. 5 500. Two of the outcomes, "2" 602 and "12" 612 are designated as bonus outcomes. In this embodiment, as indicated in the instructions 630, if the outcome of the next throw of two standard dice yields a sum of 2 602 or a sum of 12 612, then player will win twice the total amount wagered in the current play of the game. For example, if the player has wagered \$2 on the outcome "6" 606, and \$3 on the outcome "8" 608, and the next outcome has a sum of 12, then the player will be paid twice his total wager or \$10.

It should be noted that, in this embodiment, the bonus feature increases the expected payback to the player. In order to compensate for such a variation, and still be able to continue to offer this game at a profit, the house may have reduced some of the game rewards. For example, the reward ratio for the outcome "5" 605 has been reduced from 8 to 1 521 in an embodiment corresponding to FIG. 5, to 7 to 1 621 for an embodiment corresponding to FIG. 6. In one optional implementation of this embodiment, players need not place a bonus wager in order to receive a bonus reward. In an alternate implementation of this embodiment, a bonus wager may be a condition precedent for receipt of, or participation in, a bonus reward.

FIG. 7 illustrates an alternate embodiment of the present invention applied to a dice sum game 700 where the bonus reward is the opportunity to obtain additional reward opportunities should a bonus triggering outcome be generated. In the optional embodiment illustrated, the throwing of "doubles," i.e. where the value on both dice are equal, in other words combinations of 1,1 or 2,2 or 3,3 or 4,4 or 5,5 or 6,6, constitutes such a bonus triggering outcome. In alternative embodiments, other outcomes may be used. The player may wager on any of the outcomes 702 through 717. While outcomes "2" through "12" 702-712 can all be attained in a single roll of the dice, outcomes "13" through "17" 713-717 can only be attained by rolling a bonus a double, and then adding the sum of the additional roll awarded. For example, should a player wager on outcome "6" 706 and double 3's were thrown, the player would win 6:1 on his "6" wager 706. However, as a bonus triggering outcome had been thrown, play continues with all wagers standing, independent of wagers placed on "6" 706. Whatever sum is next thrown will be added to the sum of the dice comprising the bonus triggering outcome to generate a new dice sum. For example, if the second roll yields a sum of 10, then the resulting outcome is 10 beyond the current sum or $6+10=16$. If the player has a wager on "16" 716, such a player will be rewarded at a payoff of 64:1. Furthermore, if the player's 2nd roll was a 12, then the resulting outcome would be 12 beyond the current 6, which, as this layout utilizes an equivalent of modulo 16 arithmetic, would yield an outcome of 2. In addition, as, in the optional embodiment illustrated, a roll of 12 is double, and hence a bonus extending outcome, the player gets another roll of the dice, with all wagers still standing, with the starting sum now equal to 2. In an optional implementation of this embodiment, a special bonus could be rewarded to all players any time the bonus sum exceeds 17, i.e. "wraps around." For example, any reward paid after having gone around the board once could result in the reward amount being twice as large as normal.

FIG. 8 depicts an alternate embodiment 800 of the game previously depicted in FIG. 7700 where, in the present

embodiment, selected outcomes 805, 809, 813, 817 have been designated to receive bonus outcomes. The bonus "?" 805 arises for an outcome of 5, the bonus "???" 809 arises for an outcome of 9, and the bonus "?????" 813 arises for an outcome of 13. In the optional implementation illustrated, the "?" bonus, the "???" bonus, and the "?????" bonus each result in an effect determined at random. Such effects may be accorded as a random relocation to another outcome spot on the board, the ability to throw the dice again from that spot, the granting of a static reward, the granting of a random reward from a series of possible rewards, or even the ending of the game with no reward issued. The potential outcomes, as well as the probabilities of random selection of such potential reward may optionally vary for each such bonus outcome. This game 800 also features a BONUS spot 817 which, as indicated by the game instructions, will result in a reward being paid which is equal to seven times the sum of all placed wagers. Flow logic for this game is presented in FIG. 15.

FIG. 9 depicts an optional embodiment 900 of the implementation of the present invention which permits of combination wagers on bonus sums. Specifically, there are a new wager opportunities 931 through 934 for combinations of outcomes. A wager on 931 is rewarded at 4.5:1 on an outcome of a "2", "3" or "4." A wager on 932 is rewarded at 1.75:1 for an outcome of "6", "7" or "8," and so forth.

FIG. 10 shows a logic flow chart of one embodiment of this invention. The player places his wagers 1020 and starts the game 1021. Once the wagers are committed, we determine whether or not this is a bonus round. For one optional implementation of this invention as applied to a Roulette-based game, this could involve the random selection of the roulette ball where at least one designated ball, optionally identified by color, indicates a bonus round. For a Money Wheel-based game, this might optionally involve the random cycling of light colors, at least one of which colors being associated with a bonus round. Alternately, this could involve other selectors such as a secondary spinning wheel, dice or other indicia. The standard game is played out 1023 and an outcome determined. If this outcome was not predicted and wager upon by the player 1024 then the game is over 1050. If the outcome does match a placed wager, then the actual reward is determined based on whether or not this is a bonus round 1025. If it is not a bonus round, then winning outcomes are paid at the standard rate 1040 and the game ends 1050. If it is a bonus round, then the winning outcomes are paid at the higher bonus rate 1026 before the game ends 1050.

Though not shown in this figure, it would also be possible to support different bonus reward structures based upon the bonus selection. For example, in a Roulette-based game, the silver ball could indicate a standard pay while a blue ball indicates a 2x pay and a yellow ball indicates a 3x pay.

FIG. 11 illustrates the flow chart of an alternate embodiment of this invention. The player places his wagers 1120, the game is started 1121 and the game outcome is determined 1122. If the outcome is not a bonus outcome 1123, then game reward evaluation is performed 1140 to determine whether a game reward should be paid 1141. If this outcome is a bonus outcome, and if the game is defined to allow wagers to be placed on a bonus outcome 1124 and if one or more wagers were made on the bonus outcome 1126 then a reward is paid against said wagers 1142 game. Irrespective of whether or not bonus outcomes are enabled or whether or not bonus outcome wagers were paid and placed, the bonus outcome activates a bonus round 1125.

FIG. 12 depicts the flow chart of yet another embodiment of this invention, illustrating one possible bonus outcome activation. All wagers from the original game stand 1220 and

11

another game round is played out **1221** and **1222**. If the outcome is not the bonus again **1223**, the outcome is compared against the placed wagers **1240** and winnings are paid against such correctly matching wagers **1241**, but an adjusted reward rate, typically higher than the normal. An example of such would be to pay out twice as much as usual in the bonus round vs. in a standard round.

A bonus triggering outcome achieved during a bonus round is resolved according to prespecified game rules **1225**. This may optionally include activating an additional bonus round at the same reward levels, or activating another bonus round at a modified reward schedule. In one such implementation, this could cause all rewards to be tripled, rather than doubled. In another such implementation, this could cause all wagers not placed on the bonus outcome to lose. Where the game permits players to place wagers directly on a bonus outcome, then another bonus outcome during a bonus round could lead to special rewards for such bonus wagers.

FIG. 13 portrays yet another flow chart of an alternate implementation of this invention, in particular showing one possible bonus outcome activation. In this implementation, all wagers from the original game stand **1320** and the first of at least two game rounds is played out **1321**, **1322**. If the outcome is not the bonus again **1323**, the outcome is compared against the placed wagers **1340** and rewards are paid against such correctly matching wagers **1341**. Such rewards could be played out at standard rates or alternatively at special bonus round rates. If the outcome is a bonus outcome, then it can be handled as discussed above. Once the first bonus round is played out, a second bonus round is likewise played out with all wagers from the original game continuing to stand **1326**, another round being played out **1327** and **1328** and the results evaluated and acted upon **1329**, **1342**, **1342**, **1330**. Clearly, this concept can be easily extended to allow any plurality of bonus rounds to be played out.

FIG. 14 illustrates an alternate flow chart of another bonus outcome activation. This implementation is similar to that depicted in FIG. 13, except that the multiple bonus round outcome are determined in parallel instead of sequentially. All wagers from the original game stand **1420** and the game rounds is played out **1421** where multiple outcomes are generated **1422**. Optionally, these outcomes may be mutually exclusive or completely independent of each other. Each outcome is compared against wagers placed **1423**, and winnings paid against such matching wagers **1441**. Such rewards may optionally be paid at standard rates or at special bonus round rates according to predefined game definition. If the outcome is a bonus outcome, then it can be handled as discussed in FIG. 13 above.

FIGS. 15A and 15B illustrate a flow chart for the optional embodiment previously shown in FIG. 8. The player places his wager **1520** and the game commences **1521**. The value for each of the two dice is determined **1522** by the throw of physical dice or by the random generation of values which appear on electromechanical or video dice simulations. The initial outcome is determined by computing the sum of the two dice value **1523** and this outcome is then displayed **1524**. When applied to a game such as that depicted in FIG. 8, the location on the game board corresponding to the generated outcome can be marked or highlighted. Any wager placed on the current outcome **1525** is rewarded in accordance with the predefined pay schedule **1540**. Outcomes of "7", "77", "777" **1527** initiate a ward of a bonus effect **1541**. The the bonus effect to be rewarded may be the earnings of another thrown, the payment of a reward, the random relocation to a new outcome location, the ending of the game irrespective of whether a bonus triggering outcome were generated, or other

12

such rewards as determined by random generation from a predetermined list of potential rewards.

If the bonus effect is to end the game **1542**, then the game ends **1550**, else we proceed to consider whether a bonus triggering outcome has been created. In the optional embodiment illustrated, such outcomes comprise the throwing of doubles **1529**, but in alternative implementations, other outcomes could be used. If the outcome was a "BONUS" outcome **1528** then a reward is paid, said reward being optionally computed based on all outstanding wagers **1543**. Whether a bonus is paid or not, we proceed to consider whether a bonus extending outcome has been created. Optionally such an outcome is comprised of a throw of doubles. In the optional embodiment illustrated, players may not place wagers on "?", "??", "???" or "BONUS" but in an alternate embodiment such wagers may be permitted.

Once the current outcome has been evaluated, we look at whether the last dice throw was a bonus extending outcome, which in the optional embodiment illustrated consists of a throw of "doubles" **1529**, i.e. whether the die values of the thrown dice are equal. If not, then the game ends **1550**. Else if doubles were thrown, the player receives another throw of the dice for which all of his current wagers stand **1531**, and the player will again be eligible for winnings based upon the generated outcome. As described previously **1522**, two dice values are generated and summed to determine the current throw total, which total is then to the outcome sum of prior throws within the current bonus round **1533** to form the new outcome sum where such computation is performed in a modular arithmetic manner to generate a sum, modulo 16, where the sum of 0 is depicted as a value of 16, and the sum of 1 is depicted as a value of **17** **1535**. Once a new outcome has been determined, processing loops back to start another round of outcome evaluation **1524**. In this sample game, there is no limit on how many bonus throws may occur within a single game. In an alternate implementation, such a limit may be designated.

In an optional embodiment illustrated, player bonus rewards are paid after each bonus triggering event and bonus outcome. In an alternate embodiment, player bonus rewards could be paid only at predesignated points within the bonus round, for example, after every m rolls, or only at the end of the bonus round.

While certain embodiments of the present invention have been shown and described it is to be understood that the present invention is subject to many modifications and changes without departing from the spirit and scope of the claims presented herein.

We claim:

1. A method for operating a gaming system having at least one display device, the method comprising:

(a) displaying a wagering station on the at least one display device, the wagering station having a plurality of wagering areas, the wagering station being configured so that each one of the wagering areas is indicatable by at least one wager indicator, the at least one wager indicator being associated with at least one wager received;

(b) displaying a rotor on the at least one display device, the rotor having:

(i) a plurality of sectors which are associated with an outcome of a Roulette-type game, each one of the sectors corresponding to at least one of the wagering areas of the wagering station, each one of the sectors having a probability of occurrence, and

(ii) at least one bonus sector associated with a bonus outcome, the at least one bonus sector having a prob-

13

- ability of occurrence which is different than the probability of occurrence of at least one of the plurality of sectors;
- (c) displaying a first spin of the rotor on the at least one display device;
- (d) indicating at least one of: (i) one of the plurality of sectors, and (ii) the at least one bonus sector on the at least one display device after the first spin of the rotor;
- (e) in response to an indication of the at least one bonus sector:
- (i) displaying a second spin of the rotor on the at least one display device, and
  - (ii) indicating on the at least one display device at least one of:
- (x) one of the plurality of sectors, and
- (y) the at least one bonus sector, and
- (f) resolving the at least one received wager based on the indication of (e)(ii); and
- (g) providing an award depending upon the resolution of the at least one received wager.

2. The method of claim 1, which includes displaying: (i) the plurality of sectors, and (ii) the at least one bonus sector arranged about a center of the rotor.

3. The method of claim 1, which includes, in response to any indication of the at least one bonus sector after the first spin of the rotor, displaying the second spin of the rotor and at least one additional spin of the rotor.

4. The method of claim 1, which includes, in response to any indication of the at least one bonus sector after the first spin of the rotor, indicating at least two of: (i) any of the sectors, and (ii) the at least one bonus sector after the second spin of the rotor.

5. The method of claim 1, which includes displaying at least one ball, wherein each indication is displayed by the at least one ball being positioned at, at least one of the sectors or the at least one bonus sector.

6. The method of claim 1, which includes displaying an area for each one of the sectors and displaying a different area for the at least one bonus sector, the displayed area for the at least one bonus sector being differently dimensioned than the displayed area for each one of the sectors.

7. The method of claim 1, which includes, in response to any indication of the at least one bonus sector after the first spin of the rotor and a placement of at least one wager on the wager station that corresponds to the at least one bonus sector, displaying the second spin of the rotor.

8. The method of claim 1, which includes excluding at least one of the sectors.

9. The method of claim 1, which includes, in response to any indication of the at least one bonus sector after the second spin of the rotor, displaying a third spin of the rotor.

10. The method of claim 9, which includes excluding at least one of the sectors.

11. The method of claim 1, which includes associating each game symbol and each bonus symbol with a first multiplier applied to the one or more wagers for the first spin of the rotor in response to at least one of: (i) the game symbols, and (ii) the at least one bonus symbol being indicated after the first spin of the rotor, and wherein each game symbol and each bonus symbol is associated with a higher, second multiplier applied to the one or more wagers for the second spin of the rotor if at least one of: (i) the game symbols, and (ii) the at least one bonus symbol are indicated after the second spin of the rotor.

12. The method of claim 1, which includes (a) associating each game symbol and each bonus symbol with a multiplier applied to the one or more wagers for the second spin of the rotor in response to at least one of: (i) the game symbols, and

14

- (ii) the at least one bonus symbol being indicated after the second spin of the rotor, and (b) causing a random selection of the multiplier from a plurality of multipliers associated with the second spin of the rotor.

5. The method of claim 1, which includes providing (a) to (g) through a data network.

14. The method of claim 13, wherein the data network includes an internet.

15. A method for operating a gaming system having at least one display device, the method comprising:

(a) displaying a wagering station on the at least one display device, the wagering station having a plurality of wagering areas, the wagering station being configured so that each one of the wagering areas is indicatable by at least one wager indicator, the at least one wager indicator being associated with at least one wager received;

(b) displaying a rotor on the at least one display device, the rotor having:

(i) a plurality of sectors which are associated with an outcome of a Roulette-type game, each one of the sectors corresponding to at least one of the wagering areas of the wagering station, each one of the sectors having a probability of occurrence based on a size of each one of the sectors, and

(ii) at least one bonus sector associated with a bonus outcome, the at least one bonus sector having a probability of occurrence based on a size of the at least one bonus sector, the size of the at least one bonus sector being different than the size of at least one of the plurality of sectors and the probability of occurrence of the at least one bonus sector being different than the probability of occurrence of at least one of the plurality of sectors;

(c) displaying a first spin of the rotor on the at least one display device;

(d) displaying a ball on the at least one display device to indicate at least one of: (i) one of the plurality of sectors, and (ii) the at least one bonus sector after the first spin of the rotor;

(e) in response to an indication of the at least one bonus sector:

(i) displaying a free bonus spin on the at least one display device, the free bonus spin being a second spin of the rotor, and

(ii) indicating on the at least one display device at least one of:

(x) one of the plurality of sectors, and

(y) the at least one bonus sector, and

(f) resolving the at least one received wager based on the indication of (e)(ii); and

(g) providing an award depending upon the resolution of the at least one received wager.

16. The method of claim 15, wherein the displayed area of the at least one bonus sector is larger than the displayed area of each one of the sectors.

17. The method of claim 15, which includes providing (a) to (g) through a data network.

18. The method of claim 17, wherein the data network is an internet.

19. A gaming device comprising:
at least one display device;
a wagering station having a plurality of wagering areas, the wagering station being configured so that each one of the wagering areas is indicatable by at least one wager indicator, the at least one wager indicator being associated with at least one wager received;

15

a rotor having:

- (i) a plurality of sectors which are associated with an outcome of a Roulette-type game, each one of the sectors corresponding to at least one of the wagering areas of the wagering station, each one of the sectors having a probability of occurrence, and
- (ii) at least one bonus sector associated with a bonus outcome, the at least one bonus sector having a probability of occurrence which is different than the probability of occurrence of at least one of the plurality of sectors;

the rotor operable to spin a first spin to indicate at least one of: (i) one of the plurality of sectors, and (ii) the at least one bonus sector;

the rotor operable to spin a second spin to indicate at least one of: (i) one of the plurality of sectors, and (ii) the at least one bonus sector in response to an indication of the at least one bonus sector;

at least one processor; and

at least one memory device which stores a plurality of instructions, which when executed by the at least one processor, cause the at least one processor to operate with the at least one display device to carry out a plurality of steps in response to an indication of the at least one bonus sector, the steps including:

5

10

15

20

16

- (a) display the first spin of the rotor,
- (b) indicate at least one of: (i) one of the plurality of sectors, and (ii) the at least one bonus sector after the first spin of the rotor,
- (c) in response to an indication of the at least one bonus sector:
  - (i) display the second spin of the rotor, and
  - (ii) indicate at least one of:
    - (x) one of the plurality of sectors, and
    - (y) the at least one bonus sector, and
- (d) provide an award depending upon a resolution of the at least one received wager based on the indication of (c) (ii).

20. The gaming device of claim **19**, wherein the at least one display is configured to display the wagering station and the rotor.

21. The gaming device of claim **19**, which includes a ball operable to indicate at least one of: (i) one of the plurality of sectors, and (ii) the at least one bonus sector.

22. The gaming device of claim **19**, wherein the probability of occurrence of each one of the plurality of sectors and the probability of occurrence of the at least one bonus sector are based on a size of the sector and the at least one bonus sector.

* * * * *
